UNITED STATES PATENT OFFICE.

SANFORD A. MOSS, OF LYNN, MASSACHUSETTS, ASSIGNOR TO GENERAL ELECTRIC COMPANY, A CORPORATION OF NEW YORK.

ELASTIC-FLUID TURBINE.

1,130,187.

Specification of Letters Patent. Patented Mar. 3, 1915.

Application filed April 3, 1912. Serial No. 829,226.

To all whom it may concern:

Be it known that I, SANFORD A. MOSS, a citizen of the United States, residing at Lynn, in the county of Essex, State of Massachusetts, have invented certain new and useful Improvements in Elastic-Fluid Turbines, of which the following is a specification.

The present invention relates to turbines, and particularly to turbines having a conduit leading from an intermediate stage through which motive fluid is adapted to pass. Such a conduit may be for admitting low pressure steam for mixed pressure operation, for extracting steam for industrial purposes, or for use as an auxiliary exhaust when the turbine is operating non-condensing. In such turbines when operating non-condensing, which means that one or more of the low pressure stages are running idle, there is danger of over-heating the last stage wheels. This may occur when for any reason the condenser vacuum is lost.

The object of the present invention is to provide means for obviating this danger, and to this end I provide an automatic relief valve connected with the final stage and which is arranged to open automatically whenever the condenser vacuum is lost, and to reclose when the same is regained. This insures the circulation of motive fluid through the final stages to prevent over-heating.

In turbines of this general type it is customary to provide a stage valve for maintaining constant pressure in the intermediate stage to which the conduit connects, such stage valve being either under the control of suitable governing devices whereby it acts to maintain constant pressure in such stage, or under hand control. In carrying out my invention in connection with a machine of this type, I provide along with the automatic relief valve, a suitable stop for limiting the movement of such stage valve toward closed position. This insures that the circulation through the lower stages of the machine will never be entirely cut off.

Referring to the drawing, Figure 1 is a plan view of a more or less diagrammatic nature illustrating an embodiment of my invention, and Fig. 2 is a section through one form of automatic relief valve which I may use.

3 indicates a high pressure turbine receiv-

ing motive fluid by way of conduit 4 and exhausting through conduit 5 to the condenser 6. Connected with an intermediate stage is the conduit 7 having arranged therein a suitable valve 8. This conduit may be used for supplying low pressure motive fluid for mixed pressure operation, for extracting motive fluid for industrial purposes, or for use as an auxiliary exhaust in order to increase the efficiency of the machine when operating non-condensing. These uses are all well understood in this art.

9 indicates diagrammatically a stage valve controlling the flow of motive fluid through the passages 10 to the final stage or stages 70 of the machine. As already stated this stage valve may be controlled in any suitable or desired manner.

11 indicates a stop carried by the valve 9 and adapted to limit its movement toward closed position. In this connection it is to be understood that this showing is wholly diagrammatic. The turbine is shown as driving a generator 12.

Leading from the final stage of the turbine, as from the conduit 5, is a pipe 13 in which is arranged the atmospheric relief valve 14, biased to open position by suitable means, as by the weight 15. One side of the valve is subjected to the pressure existing in the condenser, and the other side to a substantially constant pressure, as atmospheric. The valve is preferably water sealed as indicated at 16.

In operation, so long as the condenser vacuum is maintained, the constant pressure on the one side of the valve will be sufficient to seat the same against the biasing force of the weight. If, for any reason, the vacuum is lost, the pressure in the condenser will tend to equalize the constant pressure and the biasing force will open the valve. Should the condenser vacuum be restored, the valve will be automatically reseated, as will be obvious. When the valve 14 is unseated, due to the vacuum being lost, the pipe 13 forms in substance an exhaust passage to the atmosphere in parallel with the conduit 7 so that there will be more or less circulation of steam through the lower stages which will act to prevent overheating.

In accordance with the provisions of the patent statutes, I have described the principle of operation of my invention, together with the apparatus which I now consider to

represent the best embodiment thereof; but I desire to have it understood that the apparatus shown is only illustrative and that the invention can be carried out by other means.

What I claim as new and desire to secure by Letters Patent of the United States, is:—

1. The combination with a turbine having a conduit leading from a region of intermediate pressure, and a condenser into which the turbine exhausts, of a valve controlling a passage leading from a region of lower pressure, and means for automatically opening said valve when the turbine changes from condensing to non-condensing operation so as to insure a circulation of fluid through the final stages of the machine at all times.

2. The combination with a turbine having a conduit leading from an intermediate stage and a condenser into which the final stage exhausts, of a vent pipe connected with the final stage of the turbine, a normally closed valve in said pipe, and means for

automatically opening said valve when the condenser vacuum is lost and restoring it when the vacuum is regained so as to insure a circulation of the fluid through the final stages of the machine at all times.

3. The combination of a turbine having a plurality of stages, a conduit leading from an intermediate stage, a stage valve controlling the passage of steam from such stage to the next lower, a stop for limiting the movement of the stage valve toward closed position, a condenser into which the turbine exhausts, and an automatic relief valve connected with the final stage of the turbine and adapted to open when the turbine changes from condensing to non-condensing operation.

In witness whereof, I have hereunto set my hand this 31st day of March, 1914.

SANFORD A. MOSS.
